UNITED STATES PATENT OFFICE.

HARRY LANGER, OF MILWAUKEE, WISCONSIN.

DOOR FIXTURE.

Application filed July 18, 1923. Serial No. 652,814.

To all whom it may concern:

Be it known that I, HARRY LANGER, a citizen of the United States, and resident of Milwaukee, in the county of Milwaukee and State of Wisconsin, have invented certain new and useful Improvements in Door Fixtures; and I do hereby declare that the following is a full, clear, and exact description thereof.

10 This invention relates to door fixtures and is particularly directed to mechanism for temporarily holding a swinging door open.

Objects of this invention are to provide a door fixture in which manually operable 15 means are arranged adjacent the outer or moving portion of the door and readily accessible to the operator, in which a pivotally mounted bar is provided with means at its outer end for latching the door in 20 open position, and in which a manually operable release is carried by the outer end of such latching bar.

Further objects are to provide means for retaining a door in open position, which 25 may be readily operated with a small effort, which is of sturdy and simple construction, which may be cheaply manufactured, and which may be readily applied.

Embodiments of the invention are shown 30 in the accompanying drawings, in which:—

Figure 1 is a plan view of a pair of swinging doors with a portion of the door casing and the latch mechanism illustrated.

Figure 2 is a sectional view on the line 35 2—2 of Figure 1.

Figure 3 is a view on the line 3—3 of Figure 1.

Figure 4 is a detail view on the line 4—4 of Figure 1.

40 Figures 5, 6, 7, 8 and 9 are detailed views corresponding to Figure 4 showing further modified forms of the invention.

This latching mechanism is primarily designed for a swinging door 1 which is 45 hingedly carried by a door casing 2—the door being preferably hinged to the uprights 3 of such casing, as illustrated in Figures 1 and 2.

An arm 4 is pivotally carried adjacent its 50 inner end by means of a bracket 5 secured to the under side of the upper portion of the casing 2. This bar may conveniently be of channel iron, as shown in Figures 2 and 3, and is provided with a notch 6 adjacent its outer end. A bracket 7 is secured to the inner face of the door and is provided with

a rectangular opening 8 through which the arm 4 is adapted to slide. This bracket, it will be seen from Figures 1, 2 and 4 has a relatively thin portion 9 which is adapted to seat within the notch 6 of the arm when the door is in full open position, as shown in Figures 1 to 4, thus when it is desired to open the door, it is merely necessary to swing the door outwardly in the usual manner, the bar 4 sliding freely within the opening 8 of the bracket 7 and its notch 6 finally engaging the portion 9 of such bracket and moving into latching position.

Manually operable means for releasing 70 the bar is carried by the outer end of the bar 4, and in the form illustrated in Figures 1 to 4, comprises a lever 10 pivotally secured, as indicated at 11, to the bar 4. The outer end of this lever is provided with a rod 12 which may terminate in a manipulating hand eyelet 13.

The operation of the apparatus is as follows:—The door, as stated, is swung into its open position in the usual manner and 80 the bar 4 drops into latching position and thus securely retains the door open. When it is desired to release the bar, it is merely necessary to pull downwardly upon the rod 12. The lever 10 rocks about the portion 85 9 of the bracket and elevates its pivot 11 thus raising the bar and detaching it from the bracket.

Figure 5 shows a further form of the invention in which the bar 14 is devoid of 90 notches and instead a notch 15 is provided in the cam shaped portion of the latching lever 16. This lever is pivoted intermediate its ends to the outer end of the bar 14, as indicated at 17 and is equipped with a control rod 12. In this form of the invention, it is merely necessary to swing the door open in the usual manner, the portion 9 of the bracket riding upon the cam shaped face 18 of the latching lever until it finally 95 engages the notch 15 of such lever. To release the device, it is merely necessary to pull downwardly upon the rod 12.

Figure 6 shows a further form in which the arm 18 is also devoid of notches and carries a latching lever 19 at its outer end, which is pivotally joined thereto and is provided with a notch 20 intermediate its ends adapted to receive the portion 9 of the bracket after such portion has raised the latching lever 19 by sliding along the cam face 21 of such lever. In this case, the de-

vice is detached by pushing up on the rod 12.

Figure 7 shows a further form of the invention in which the arm 22 is provided with a notch 23 adjacent its outer end, and in which a detaching lever 24 is pivoted as indicated at 25 intermediate its ends. In this form of the invention, the detaching is effected by pressing upwardly upon the rod 10 12 thus forcing the inner end of the lever 24 downwardly and raising the bar 22 from locking engagement with the portion 9 of the bracket.

Figure 8 shows a further form in which 15 the arm 26 is provided with a locking shoulder 27 adjacent its outer end and with a beveled face 28 leading to such shoulder, as shown in dotted lines in such figure. The lever 29, in this case, is pivoted at 30 20 adjacent the outer end of the arm 26 and is provided with a locking shoulder 31 adjacent its inner end. A pin 32 may be provided to prevent the lever's falling below the lower edge of the arm 26. In this form of 25 the invention, the portion 9 of the bracket is held between the shoulder 27 of the arm and the shoulder 31 of the lever 29. When it is desired to detach the device, it is merely necessary to pull downwardly upon the 30 35 rod 12 thus moving the shoulder 31 upwardly out of engagement with the portion 9 of the bracket. The door may then be readily closed and the bar 26 will ride upwardly due to the slanting surface 28 thereof, over the portion 9 of the bracket.

Figure 9 shows a further form of the invention in which the bar 33 is provided with a locking shoulder 34 adjacent its outer end and with a beveled or slanting portion 40 35 leading to the base of such locking shoulder, as shown in dotted lines. The inner locking shoulder 36 is carried by the lever 37 which is pivotally mounted adjacent its inner end, as indicated at 38, to the outer 45 portion of the bar 33. This form of the apparatus is detached by pushing the rod 12 upwardly thus moving the inner shoulder

36 out of engagement with portion 9 of the bracket.

It will thus be seen that a door fixture 50 has been provided which will latch the door in open position, which may be operated by manual means located adjacent the outer end of the locking arm, and within ready access of the operator as he grips 55 the outer portion of the door preparatory to closing it.

It will further be seen that only a small effort need be made to effect detachment and that the device may, therefore, be easily 60 operated.

It will further be seen that neither excessive effort is required nor excessive strains placed upon any portion of the apparatus during detaching operation. 65

It is further to be noted that the device is extremely simple, may be most readily produced and attached, and is of sturdy and substantial construction not likely to get out of order. 70

Although a few forms of the invention have been described in considerable detail, it is to be understood that the invention may be variously embodied and is to be limited only as claimed. 75

I claim:

The combination of a casing, a door pivotally carried thereby, a bar having its inner end pivoted to said casing and having a notch formed in its outer end, a bracket 80 rigidly carried by said door for slidably receiving said bar and cooperating with said notch to latch said door in open position, and a manually operable lever pivoted to said bar adjacent the outer end thereof for 85 raising said bar from said bracket to disengage said bracket from said notch, said lever being adapted to bear against said bracket when elevating said bar.

In testimony that I claim the foregoing I 90 have hereunto set my hand at Milwaukee, in the county of Milwaukee and State of Wisconsin.

HARRY LANGER.
